(57) **CLAIM**
The ornamental design for a CPTS constant product temperature scanner, as shown and described.

DESCRIPTION

FIG. 1: is the laser portion of the device shown as the front right angle.
FIG. 2: is the laser portion of the device shown as the front view.
FIG. 3: is the laser portion of the device shown from a left side view.
FIG. 4: is the laser portion of the device from a direct side view.
FIG. 5: is the control box portion from a left side angle view.
FIG. 6: is the control box front view with the multi-point pyrometer display showing.
FIG. 7: is the control box front view with the system set up display showing.
FIG. 8: is the control box front view with the scan programming display showing; and,
FIG. 9: is the control box front view with the system enabled display showing.
The “CPTS” constant product temperature scanner is a new design for saving energy using your refrigerator and freezer. It is laser operated device that has a 360 Degree arm that swings into preprogrammed positions to establish the product temperature such as a food product and when it drops below an accepted temperature it will cause the refrigeration unit to activate and bring the temperature back to an acceptable temperature.
